Primary Examiner — Cynthia Ramirez*Assistant Examiner* — Michael A Maharajh(74) *Attorney, Agent, or Firm* — Jeffer Mangels; Butler & Mitchell LLP; Brennan C. Swain Esq.**CLAIM**

The ornamental design for a massage element, as shown and described.

DESCRIPTION

FIG. 1 is a top perspective view of a massage element showing our new design;

FIG. 2 is a top plan view thereof;

FIG. 3 is a bottom plan view thereof;

FIG. 4 is a front elevational view, the rear elevational view, right side elevational view and left side elevational view being mirror images thereof;

FIG. 5 is a bottom perspective view thereof; and,

FIG. 6 is a front elevational view thereof with a portion shown in cross-section.

The broken lines in the drawings are for the purposes of illustrating portions of the massage element, which form no part of the claimed design.
